Primary Examiner — George D. Kirschbaum*Assistant Examiner* — Denis Houyoux(74) *Attorney, Agent, or Firm* — Lerner David LLP(57) **CLAIM**

The ornamental design for a bus bar for battery, as shown and described.

DESCRIPTION

FIG. 1 is a front perspective view showing the overall configuration of a bus bar for battery according to our new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is a bottom perspective view thereof.
